UNITED STATES PATENT OFFICE

DONALD A. NEVIN, OF WAYNESBORO, PENNSYLVANIA

CARD INDEXING DEVICE

Application filed November 30, 1928. Serial No. 322,943.

My said invention relates to card indexing devices and it is an object of the same to provide a simplified device of this character along the general lines of my Patent 1,662,534, March 13, 1928 and my application 205,000 filed July 11, 1927 now Patent 1,739,168, December 10, 1929. It is an object of this invention to eliminate numerous working parts and to provide for more ample and convenient 10 expansion of the index file, particularly in cases where alphabetical filing is preferred.

Another object of the invention is to provide an improved card-container tray with means on the tray for guiding the boxes therein.

Still another object is to provide means for facilitating operations of raising and lowering all the cards in the tray.

Referring to the drawings, which are made a part of this application and in which similar reference characters indicate similar parts:

Fig. 1 is a perspective of the forward portion of a card index machine embodying my improvements,

Fig. 2, a vertical longitudinal section of the same, certain parts being omitted for clearness of disclosure,

Fig. 3, a vertical transverse section of the same, with a card container box lowered position, and partly broken away,

Fig. 4, a detail, partly in section, of one of the guide tabs or clips to the attached to the card-container boxes.

Fig. 4^a, an end view of the guide tab shown in Fig. 4,

Fig. 5, a perspective of a card-container box,

Fig. 6, a partial front elevation of a card tray,

Fig. 7, a detail of a selection key and coacting parts, the key being in lowered position,

Fig. 8, a similar view with the key in normal elevated position.

Fig. 9, a similar view of a rejection key and coacting parts,

Fig. 9^a, a fragmentary section of parts shown in Fig. 10.

Fig. 10, a fragmentary section substantially 60 on line 10—10 of Fig. 2, certain parts being omitted for clearness and other parts being in positions different from those of Fig. 2,

Fig. 11, a transverse section of a modified form, and 65

Fig. 11^a, a section on line 11^a—11^a of Fig. 11,

Fig. 12, a detail illustrating a special use of guide tabs.

In the drawings reference character 10 indicates a tray for holding a number of card-container boxes, this tray being located on a mechanism box or case 12 containing card-selecting mechanism and being held in place by dowel pins 12' or the like so that one tray can readily be lifted off and another substituted therefor as in my patent above mentioned.

The mechanism case has at the forward end a group of selection keys 12' which may bear indicia of various sorts, but are here shown as being provided with the letters 60 65 of the alphabet. In a small card system a single tray may have merely one separate card-container box for each letter of the alphabet as shown, or the container boxes

may be arranged in groups as in my said patent. The card-container boxes as best 70 shown in Fig. 11 extend to the full height of the cards or approximately so, the high partitions 89 shown in my Patent 1,662,534 being dispensed with. This renders it possible 75

to attach guide and manipulating tabs or 80 clips such as indicated at 13 to the upper edge of the forward wall of each container box in cases where the container boxes each contain

all the cards for words or names beginning 85 with the same letter of the alphabet. If there is a group of cards beginning with the letter "A" and divided into sub-groups; e. g.,

according to the second letter of the word, then a primary clip such as shown at 13 (Fig. 90

4) or at 113 (Fig. 12) will be attached to the front wall of the first container box of the group and secondary clips will be attached to the front walls of the remaining container boxes of the group as indicated at 114 (Fig. 12). The primary and secondary clips may differ only in the indicia thereon and in their different positions, the secondary clips being farther to the right. In this way, for example, cards for words or surnames having the second letter "i" will be found in one of the boxes containing sub-groups in group "D"; e. g., such names as Diehl, while cards having a second letter "o" or surnames having the second letter "o" will be found in another box; i. e., such names as Doe, it being understood that a sub-group may include any desired part of the alphabet, e. g., names from Aaron to Exnicious might be in one sub-group, the secondary clip or clips being correspondingly marked.

A preferred form of guide tab or clip 13 is shown in Fig. 4, where the tab 13 has a lateral slot through which a slip of paper may be inserted, such paper carrying an appropriate legend, as "A". The clip may consist of two thin strips of sheet-metal 13⁵ and 13⁶ with a bar 13² between them and secured to them, as by spot-welding. Bar 13² has a lug 13³ for engagement with any one of a set of notches 13⁴, in the container box wall, so that any box may be either a primary or a secondary container.

The card-container boxes each have a front wall 15, a rear wall 16, and lateral projections 15', 16' on the front wall extending through slots in side frame members 17, 18 of the tray whereby the boxes are guided for up-and-down movement in the tray. The boxes as shown in Fig. 5 are generally similar to those disclosed in my said patent except as stated, the front and rear walls being separate except where connected by parts 22, 27, 28, 29 of a continuous strip of metal welded or otherwise attached to the side walls at the lower right-hand corner, and parts 23, 24, 25 and 26 of another like strip at the lower left-hand corner. The boxes are partly open at the bottom to expose tabs 19, 20 on the cards 21 which have inclined edges near the bottom corners to slide on inclined faces of parts 22 and 23 in the container box as in said patent, the cards being movable to the left in a selecting operation hereinafter described to bring them into a position where the rounded lower right-hand corner of the card will engage with the upper end of the inclined portion 22 to hold the card or cards so moved against accidental return movement to the right due to jarring of the tray or the like it being understood that the card moves slightly upward to allow its corner to pass part 22 and then drops to permit the rounded edge of the card to engage behind part 22. (See dotted lines, Fig.

3.) For this purpose the projection at the lower right-hand corner in my patent, or in present Fig. 11, is merely cut off on a radius. An incline at 25 prevents excess movement of the cards to the left. The bottom portions 70 of the container on which the cards normally rest are indicated at 26 and 27, the container being otherwise open at the bottom. Downwardly extending flanges 30, 30, 31, 31 (Figs. 3 and 5) coact with longitudinal guide 75 rails 32, 32' and 33 for guiding the container boxes to cause them to move diagonally instead of vertically or horizontally. The container boxes have a compound movement and notches are provided at 66 (Fig. 3) at 80 the right-hand end of walls 15 and 16 opposite guide rail 32' to avoid interference with the lateral component of the final part of such movement. For this purpose also the upper ends of extensions 31 (Fig. 3) are 85 rounded off as shown at 67 so as not to strike against rail 33.

The container boxes are guided in the first part of their diagonal movement downward and to the right by engagement of rail 33 with the edges of flanges 31, 31 at the left of said rail and by engagement of rail 32' with the adjacent edges of flanges 30, 30. As a container box nears the end of its movement the left-hand lower corner of the box strikes a downwardly-inclined cam rail 65 which extends underneath all the boxes and which guides the box in a direction more nearly approaching the horizontal. The boxes are preferably beveled at this corner, though not necessarily so. At the lower right-hand corner the flange 30 moves away from rail 32 and its lower part comes to bear on a horizontal supporting rail 65' extending underneath all the container boxes, on which rail 90 this end of the box rides farther to the right and the box comes to rest at a point a little beyond the position indicated in Fig. 3. At this time the notch 66 accommodates rail 32', which otherwise would be struck by flanges 30, 30. When returned by the springs 34 95 the containers will move upward and to the left to the limit of contraction of the springs or to such a distance as permitted by the side of the tray, the diagonal edges of a container 100 at the right of rails 32 and 33 guiding it and limiting its movement to the left. Springs 34 are attached at one end to parts 25 of the container boxes and at the other end to a rock-arm 35 on a rod 35' extending along 105 the tray, normally holding the container boxes in elevated position.

A pin 36 is shown on the container box in Fig. 3 for coacting with a tooth 37 of a comb 38 (Fig. 2) which extends along the tray, each tooth being arranged to coact with a pin 36 of one of the container boxes. The pin 36 also serves as a spacer for the parts 31, 31. The comb is mounted on a shaft 39 having at its forward end a beveled gear 40 110

coating with a beveled gear 41 on a shaft 42 extending across the front end of the mechanism box. A crank 43 with an operating handle (or "audit handle") 44 is attached to the right-hand end of the shaft. The operating handle 44 is used when all the boxes are to be lowered, as for finding misplaced cards, and at such time the combined tension of all the springs 34 would cause the operation of the handle to require considerable exertion, besides tending to throw the boxes up with undesirable force on inadvertent release of the handle with consequent possible injury to the cards or the machine or the rebound. To avoid this the tension of all the springs is relieved wholly or in part by means hereinafter described, prior to a selecting operation of the machine.

Underneath the card-container boxes I have provided means for limiting the movement of the cards to the right as each card-container box is depressed, such means consisting in bars 52 and 60 extending longitudinally of the tray in position to engage edges 52' and 60' on the cards. For selectively offsetting the cards I have shown a guide 53 for selection rails 54 with cam rails 55 moving them upward as in my said patent, except that the slots 55' are vertical and of equal width from top to bottom. As an obvious variation the rejection rails could be connected directly to the keys and provided with cams or the like coating with means on the tray to lift the rails as they are moved endwise. Rejection rails (not shown) such as in my patent above referred to, act on the rejection tabs 20 to return offset cards into the normal position, the selection keys being locked down by means such as shown at 179 in said patent and being released on depression of a release key such as shown in Fig. 26 of said patent or by depression of a rejection key or another selection key. Of course several selection keys can be depressed simultaneously by the operator, if desired, after which a rejection key may be operated to cause the return of cards not wanted.

A rail at 65' supports the containers at their right-hand end when all or any of them are lowered and after they move away from rail 32 (Fig. 3). The rail 65' extends under all the containers but stops short of shaft 42, it being of the same length as cam rail 65.

The selection and rejection keys may be similar or even identical in shape with the keys shown in Fig. 26 of my patent above-mentioned, the upper operating extensions 73, 74 being arranged at various points with reference to the body of the key, according to the row in which they are to be located. For the selection keys a key-retaining bail 75 pivoted at 76 on brackets 76' attached to the mechanism case is provided at its lower end with a detent 77 for engaging in a cut-

out at 78 to hold down one or more depressed keys. A spring 79 serves to draw the bail to the left and springs 80 pull the keys upward.

The rejection keys (Fig. 11) indicated at 80' in Fig. 1, have no cut-out for engagement by the bail and hence are returned to upper position by springs 81 as soon as released. These keys are provided with horns 82 adapted to bear on a rod 82' connecting rockers 83 pivoted at 76 and located at opposite ends of the key-board. The rod 82' depresses links 84, which are pivoted at 85 to the arms of bail 75, there being one link 84 at each end of the bail 75. In addition to their rocking movement links 84 move forward and back with key retaining bail 75. A spring 100 holds each link 84 in raised position. All the keys are located in the upward extension 86 at the front of case 12 and the links 84 are adapted when the bail 75 is in key-unlocking position to engage notches at 87 in a safety slide 87' slidably mounted on the rear wall 86' of extension 86 and held by screws 89. A spring 88 pulls the safety slide to the right against the classifying lever 91. A stud 90 on the slide extends through a slot 90' in wall 86' into the path of the lever, which is pivoted at 92 on the front of tray 10 (see Fig. 6) and has a handle 93 at its upper end above the tray. A beveled stud 94' (Figs. 2 and 6) on the tray locks the lever against movement until the lever is sprung forward sufficiently to clear the stud, the stud being beveled to permit the lever to slip over it in a counter-clockwise movement, but holding the lever against clockwise movement. The lever is limited in its swing by a stud 95 extending into a slot at 96 on the tray and is connected by a link 97 to a rock-arm 98 fixed to shaft 35' by means indicated at 68 in Fig. 6. The stud 94' holds the classifying lever 91 in the position of Fig. 6, thereby maintaining shaft 35', springs 34 and connected parts in the position of Fig. 3 and holding the safety slide in the position of Fig. 10, so that links 84 and retaining bail 75 may move about 76 as an axis, thereby permitting up or down movement of the selection keys.

In selecting a card from a known approximate location; e. g., a card-container box indicated by the tab 13, Fig. 3 or 113, Fig. 11, the resistance of one or two of the springs 34 is so slight that the box may be lowered by pressing down on tab 13, but because it would be very impractical or almost impossible to depress 50 or more of these boxes with the fingers (when the location of the card or cards is not known) the classifying lever 91, comb rod mechanism 37, etc., and the audit handle 44 are provided to (1) relieve the tension of springs 34 so that the containers may be moved downward and to the right without such force as would be necessary to move them upward, and (2) to hold the containers in the position of Fig. 10 so that the selection keys may be depressed without the necessity of holding the tray in a horizontal position.

sary to overcome the resistance of the springs and (2) lower the entire mass of cards simultaneously (3) give a complete sidewise motion to all of the cards to the right except those obstructed by the predetermined elevated selection rail or rails.

Operation

In the operation of the form of my device above described a tray 10 containing cards is placed on the case 12, thereby bringing the lever 91 into engagement with stud 90. The lever moves the safety slide to the left as the box is placed on the tray (in Fig. 10) until slots 87 register with the ends of links 84. This permits the key-retaining bail to be rocked by depression of a key and, in effect, unlocks all the selection keys, which heretofore were locked up by the bail. The lever 91 being still held by beveled detent 94', one or more of the selection keys are now depressed to position selection rails 54 according to the initial of the first name of a party whose card is to be located, or according to the first letter of a word or the first digit of a numeral or the like.

If it be desired to locate a card with the name of John Adams the first step is to depress the "J" key on the keyboard (Fig. 1) thus elevating the selection rail 54 in Fig. 3. Now the guide tab "A" for Adams is located, this being either a primary tab or a secondary tab, as the case may be, and the operator presses down upon the same with his finger to lower the group of cards until the diagonal downward movement of the cards is arrested by bar 52 and stop 60 (Fig. 3) before the container reaches its lowermost position. In the downward movement of the container box it also moves to the right and into position for engagement of the tabs on "J" cards with the selection rail 54, but as this rail stops the movement of the selected cards, before the container is arrested, the selected cards will be offset to the left out of the group into a position corresponding to that shown in broken lines in the modified form in Fig. 11, the non-selected cards being in the position indicated (in part) by unbroken lines, and the selected cards will be so positioned that their rounded outer corners 21' will engage the end of part 22 and will be held in offset position as the box rises, moving all the cards up and keeping offset cards in the same relative position to other cards as that indicated in Fig. 3.

As the containers approach the lower limit of their movement (the position shown in Fig. 3) the lower left-hand corners strike the cam-rail 65 and this causes the bodily movement of the containers to have a larger component of lateral movement toward the right with a small component of downward movement, the containers moving to the right away from guide bars 32 and 33 (see Fig. 3).

This takes place after the tabs have engaged the selection keys and increases the offsetting of the cards. It will be understood that more than one selection key may be depressed to raise the corresponding rails and that more than one container may be depressed simultaneously to select cards therefrom. The plurality of selection keys should be depressed at the same time to insure that detent 77 will engage their notches and hold them down, but additional keys may be depressed if those already down are held down by hand during such subsequent selection. The rejection keys, if such are included in the set, may be operated at any time while the safety slide is in the position shown in Fig. 10, and can only be operated before classifying lever 91 is moved to the right as hereinafter described.

Proper operation of the device requires the selection rails to be operated before depressing the card containers so as to prevent crushing of the rejection or selection tabs on the cards by operation of keys at improper times. It is therefore necessary to lock the selection keys against depression after the cards are lowered by clockwise motion of classifying lever 91. To provide for this the safety slide 87' is held in its extreme left position against the tension of spring 88 by the classifying lever 91 contacting with stud 90 mounted on safety slide 87'. A small amount of movement of the classifying lever to the right permits the safety slide 87 to follow to the right, being operated by spring 88, and a slight travel in this direction brings the slots 87 from behind the ends of the rocker arms 84 so that they are obstructed by safety slide 87'. Thereafter depression of any one of the selection keys will be prevented because the cam face at 101 bears against bail 77 and the bail is locked by the ends of rockers 84 contacting with the safety slide 87'. When the key-retaining bail is in position to lock the keys, or in idle position (Fig. 8) the rockers 84 are sufficiently forward to permit free movement of the safety slide behind the rockers, but none of the keys can be depressed when the slide is in the locking position.

It is unnecessary to lock the rejection keys because the rejection rails when operated rise up at the left-hand side of the rejection tabs and are then swung to the right for the purpose of rejecting certain ones among the selected cards. The construction and operation of the rejection rails is the same as in my former Patent 1,662,534.

Those machines which are furnished with rejection keys for the purpose of rejecting cards not desired from a selected group are provided with rejection keys similar to the selection keys except that a horn 82 is added to contact with the connecting rod 82' fastened at its ends to rocker arms 83 so that depression of a rejection key first releases the selection keys by means of the cam face 101 130

of the rejection key operating against bail 77, the selection rails 54 moving down out of the way of card tabs 19, and then the horn 82 contacts with the connecting rod 82' so that 5 continued downward motion lowers rocker arms 84 so that they are caused to pass beneath the safety slide 87', as illustrated in Fig. 2. The rejection keys are not locked by the safety slide 87' Fig. 10, because by 10 means of horn 82, rocker arms 83 and connecting rod 82' the arms 84 are given sufficient downward movement to move out of the path of slide 87' before cam 101 contacts with bail 77.

15 Should it be desired to move all the boxes down, the lever 91 is moved to the right to take the tension off the springs 34 and to allow safety slide 87' to move to the right to prevent operation of any selection keys and 20 rails. Then the audit handle 44 is easily actuated to depress all the container boxes. After whatever selection may be desired has been completed the audit handle 44 is returned and then the lever 90 is also returned 25 into place. The beveled gear mechanism controlled by handle 44 in conjunction with the combshaft and comb 37 may be used to complete to the fullest extent the movement of the boxes to the right to insure the offsetting of the cards to the greatest extent, even 30 though a selection is to be made from only a single box.

After operation of a selection key or keys the classifying lever 91 is sprung over its 35 detent 94' and moved to the right, thus permitting the safety slide to be moved into locking position by its spring 88, and also relieving the tension of springs 34 on the card containers. The operator now depresses the desired container or containers, offsetting selected cards. Still holding down the depressed containers (the safety slide being now in the position of Fig. 10) the rejection keys and rails are operated to cause return 40 of undesired offset cards to normal position in the containers. Thereupon the classifying lever is returned to the position of Fig. 6, and the containers are permitted to return to normal position under stress of springs 45 34, raising the selected cards above the mass, after which a further manual selection can easily be made in case several cards have been selected.

50 It will be understood that in a large file of cards the secondary guides will indicate the card boxes to be depressed. It will be understood also that other systems of marking the clips may be used, as for instance 55 in a numerical system card number "765" would be selected by first depressing the key corresponding to the terminal digit of the number; i. e., key "5". Then the "700" clip or guide would be located along the tray 60 and then the "60" clip or guide connected to

the "760" box would be located and depressed.

Let it be supposed that the "765" card has been misfiled. The number "5" key is now depressed as before and the operating handle 44 is pulled forward thus offsetting all cards having "5" tabs on the lower margin. The operating handle is now returned to position thus causing the elevation of all cards numbered with terminal digit "5". The lost card 70 75 may quickly be located among these cards because the cards will be in numerical order with the exception of the misfiled card. Lost names may be found in similar manner and the device may, by this means, be used for 80 classifying with a combined alphabetical or numerical index by use of a group-elevating mechanism set forth in my application above referred to and indicated in part at 52 in this application. For this purpose means are provided to give bar 52 a movement of translation to the left whereby selected cards are 85 returned to original position in their container.

Modified form

The form of the invention in Figs. 11 and 12 is generally similar to that already described, this figure showing in greater detail the elevated and offset positions of the cards, and the parts indicated by numerals 90 95 below 100 are like those in other figures. The card containers have only a right-line diagonal movement, as in my said patent, the cut-out 66 shown in Fig. 3 being omitted and the guides 131 being continued to a higher point. 100 Guide-tabs 113 and 114 are of simpler form than in the modification first described and the containers have notches 173 to hold the guide-tabs in place and the card 121 extends further to the right from the notch for rod 52. 105

Instead of relieving the tension of springs 34, means are here shown for counterbalancing it, comprising a power spring 149 to act against the tension of springs 34 and counterbalance them whereby a light pull on the operating handle will serve either to lower the card boxes or to return them to position. The spring encircles shaft 142 and is connected at one end to a fixed bracket 150. At the other end it is attached to a clutch member 146 loose on the shaft, connected to the hub 147 of a crank 143 by means of a spring-pressed pin 148 adapted to engage with any one of a number of sockets in the hub, shaped as clutch teeth to permit the pin to slip from one to the other in the well-known manner of a ratchet clutch. A number of openings such as indicated at 151 are provided in the clutch member 146, this arrangement providing for winding up the spring easily by inserting a pin wrench in holes 151 and turning the clutch member, the pin 148 slipping from one socket to another until the spring is sufficiently tight to exert an appropriate counter- 110 115 120 125 130

balancing action against the pull of the springs 34, of which there may be as many as one hundred in the tray, each exerting the same tension on the container boxes, while the weight of the container boxes varies according to the number of cards therein. This makes it possible to raise and lower all the cards in the tray with only a slight pull or push on the operating handle 144, of the 10 crank 143. The operation of the device shown in Figs. 11 and 12 is substantially the same as in the form first described, but it should be noted that the action of springs 34 is counterbalanced instead of being relieved, the part 22 engages notches 124 in the cards.

It will be obvious to those skilled in the art that various modifications may be made in my device without departing from the spirit of the invention and therefore I do not limit 20 myself to what is shown in the drawings and described in the specification but only as indicated in the appended claims.

Having thus fully described my said invention, what I claim as new and desire to 25 secure by Letters Patent, is:

1. A card index device comprising a tray, card containers in the tray, means for moving the containers transversely of the tray, cards in said containers, tabs on the cards, 30 and arresting means movable into the path of tabs on the cards for selectively engaging the tabs to check the movement of selected cards with the container.

2. A device as in claim 1, combined with 35 guiding means for causing the containers to move diagonally downward and sidewise, the arresting means checking the sidewise movement of selected cards.

3. A device as in claim 1, combined with 40 guiding means for causing the containers to move at first diagonally downward and sidewise until after lateral edges on the tabs of selected cards have engaged said arresting means and then causing them to move farther sidewise for more fully offsetting all cards except those to be selected.

4. A device as claimed in claim 1, combined with rigid clips adapted to be positioned on the containers in position for manual engagement to move the containers for the purpose described.

5. A device as claimed in claim 1, combined with rigid clips adapted to be positioned on the containers in position for manual engagement for movement of the containers, and means for holding a clip in any one of several fixed positions on its containers.

6. A card index device comprising a tray, 60 card containers in the tray, means for moving the containers selectively transversely of the tray, cards in said containers, tabs on the cards, means acting on the cards for offsetting them selectively in the containers, 65 resilient means for returning containers to

normal position, and means to inhibit the action of said resilient means.

7. A device as in claim 6, combined with means for moving all the containers simultaneously.

8. A card index device comprising a tray, card containers in the tray, means for moving the containers in planes intersecting the longitudinal axis of the tray, cards in said containers, tabs on the cards, means acting 75 on the cards for offsetting them selectively in the containers, resilient means for returning containers to normal position, and means to relieve the tension of said resilient means.

9. A device as in claim 8, combined with means common to all the containers for moving them simultaneously.

10. A card index device comprising a tray, a set of card containers in the tray, cards in said containers, means for moving the containers independently downward and sidewise in a selecting operation, independent tension springs attached to said containers to return them to normal position, a rod to which said springs are anchored under tension, and means whereby said rod may be turned to relieve the tension on the springs.

11. A device as in claim 1, combined with means on the containers adapted to engage portions of the selected cards after initial movement is completed to hold the cards in offset position during return movement of the containers.

12. A card index device comprising a tray, card containers in the tray, means whereby the containers can be moved crosswise of the tray, cards in said containers, tabs on the cards, selecting devices for checking the movement of selected cards with the containers, keys for selectively operating the selecting means, means whereby the selecting means may be locked against operation while one or more containers remain out of normal position, and means for unlocking the locking means when such containers are to be returned to normal position.

13. A card index machine including a mechanism case having selection keys, card-selecting mechanism controlled by said keys, and means for normally locking the keys against operation, combined with a removable card tray, and means on the card tray for releasing the locking means.

14. A card index machine including a mechanism case having selection keys, card-selecting mechanism controlled by said keys, a bail for locking the keys against movement, and means for normally preventing movement of the bail, combined with a removable card tray, and means on the card tray for inhibiting the action of said preventing means.

15. A card index machine including a mechanism case having selection keys, card-selecting mechanism controlled by said keys, a pivoted bail for locking the keys against 100

movement, a bar parallel to the bail, means carried by the bail engageable with notches in the bar to permit movement of the bail by the keys, means normally holding the bar in 5 a position preventing such engagement, combined with a card tray, and means on the card tray for moving said bar to a position permitting such engagement.

16. A card index machine including a 10 mechanism case having selection keys, card-selecting mechanism controlled by said keys, a pivoted bail for locking the keys against movement, a bar parallel to the bail, means carried by the bail engageable with notches in 15 the bar to permit movement of the bail by the keys, means normally holding the bar in a position preventing such engagement, a pin on the bar, combined with a card tray, and means on the card tray for moving said bar to a position 20 permitting such engagement, said means comprising a lever on the tray positioned to engage said pin, said lever being movable in a card-selecting operation to permit return of said bar to normal locking 25 position.

17. In a card index machine, a tray, a set 30 of card containers in the tray, means for moving the individual containers diagonally downward and laterally, resilient means for holding said containers in normal inoperative position, cards in said containers, selecting tabs along the lower margin of said cards, a set of selection rails individually movable 35 into the path of said tabs, depressible keys for selectively positioning said rails, means for locking said keys in up or down position, means normally preventing operation of said locking means, means to inhibit the action of said preventing means, and common means 40 for simultaneously disabling said inhibiting means and said resilient means.

18. In a card index machine, a tray, a set 45 of card containers in the tray, said containers being open along a portion of the bottom, means for moving the containers selectively diagonally downward and laterally, resilient means for holding said containers in normal inoperative position, cards in said containers, selecting tabs along the lower 50 margin of said cards, selecting means individually movable into the path of said tabs, keys for operating said selecting means, detent means for holding said selecting means against release, and means for simultaneously 55 locking said detent means against release and disabling said resilient means.

19. Card indexing means comprising a 60 plurality of card containers each having a wall parallel to the cards in such container and of approximately equal height with the cards, with notches at intervals along said wall, in combination with clips adapted to be located on said walls and lugs on said clips for engagement with said notches to hold the 65 clips in selected position.

20. A card index device comprising a tray, card containers in the tray, means for moving the containers transversely of the tray, cards in said containers, tabs on the cards, selecting devices for engaging the tabs to check 70 the movement of selected cards with the containers, keys for selectively operating the selecting devices, and rejecting means operable after the selecting means for returning cards 75 selectively to normal position in the containers.

In testimony whereof I affix my signature.
DONALD A. NEVIN.
